UNITED STATES PATENT OFFICE.

HARRY A. MILLER, OF LOS ANGELES, CALIFORNIA.

DESIGN FOR AN AUTOMOBILE.

55,070.

Specification for Design.

Patented May 4, 1920.

Application filed September 22, 1919. Serial No. 325,562. Term of patent 7 years.

To all whom it may concern:

Be it known that I, HARRY A. MILLER, a citizen of the United States, residing at Los Angeles, in the county of Los Angeles, State of California, have invented a new, original, and ornamental Design for an Automobile, of which the following is a specification, reference being had to the accompanying drawing, forming part thereof.

Figure 1 is a side elevation; Fig. 2 is a

plan view; and Fig. 3 is a front elevation of the machine showing my design.

I claim:

The ornamental design for an automobile, as shown.

HARRY A. MILLER.

Witnesses:

W. R. RUESS,
Wm. H. MAXWELL.
